UNITED STATES PATENT OFFICE.

JOHN E. POWERS, OF PIKE, NEW YORK.

GUARD FOR KEYHOLES.

1,341,439.

Specification of Letters Patent. Patented May 25, 1920.

Application filed February 19, 1919. Serial No. 278,066.

To all whom it may concern:

Be it known that I, JOHN E. POWERS, a citizen of the United States, residing at Pike, in the county of Wyoming and State 5 of New York, have invented certain new and useful Improvements in Guards for Keyholes, of which the following is a specification.

The object of this invention is to provide 10 a new and improved form of keyhole guard which is adapted to cover the keyhole on the outside of the door and prevent the insertion of any tools or a second key therein from the outside of the door while one key 15 is inserted on the inside of the door. The guard is held in place by the key that locks the door from the inside.

This and other objects of this invention 20 will be fully illustrated in the drawing described in the specification and pointed out in the claim at the end thereof.

In the accompanying drawing—

Figure 1 is a perspective view of a portion 25 of a door showing the keyhole on the inside of the door with a guard attached thereto.

Fig. 2 is a perspective view of the guard 30 protecting the keyhole on the outside of the door.

In the several figures of the drawing, like reference numerals indicate like parts.

As shown in Fig. 1, the guard comprises 35 the plate 1 which is provided with an opening 2 corresponding in outline with that of the keyhole 8 of the lock. The plate 1 is fastened to the rod 3 by means of the set screw 4 or any other suitable means. The rod or shaft 3 extends through the door which has on each side thereof suitable bearings in the face plates 5 and 9, respectively, 40 in which the shaft 3 is mounted to rotate.

The plates 8 and 9 have the keyhole 8 provided therein through which the key is inserted to operate the lock 16. The face 45 plate 5 is fastened to the door by means of the screws 6 and the face plate 9 is fastened to the door by means of the screws 11.

A disk 7 is keyed or otherwise suitably fastened to the rod 3 on the outside of the 50 door so as to swing in unison with the plate 1 and move toward and away from the keyhole in the face plate 9 and cover or uncover this keyhole. Before the key is inserted from the inside to lock the door, the

plate is swung to position in line with the 55 keyhole and the key is then passed through the holes in plate 1 and then into the keyhole where it is used to lock the door. As long as the key remains in the keyhole it will hold the plate 1 and shaft 3 from turning. In lining up the opening 2 in the plate 1 with the keyhole the plate 1 is swung to the right and this rocks the rod 3 which in turn swings the disk 7 on the outside of the door and moves it in front of the key- 65 hole in face plate 9.

As long as the key remains in position in the lock the plate 1 is prevented from turning away from the keyhole so that it will be impossible to move the outer disk 7 to 70 permit the inserting of a key from the outside. When the key is withdrawn from the opening 2 in the plate 1 the disk will uncover the keyhole on the outside of the door as soon as the plate 1 is swung to the left 75 away from the keyhole on the inside and then the lock is free to be unlocked or locked from the outside as well as the inside.

In this manner the possibility of the entrance of an intruder who may manipulate 80 the key from the outside and then unlock the door by means thereof or by means of a duplicate or pass key is prevented as long as the key on the inside remains in position in the lock and holds the plate 1 from swinging to the left which in turn prevents the disk 7 from uncovering the keyhole on the outside of the door.

In order to protect the disk 7 from being bent out, etc., to uncover the keyhole, a casing 90 is formed around it. This casing comprises the circular flange 13 and a semi-circular wall member 14 which spaces the flange from the face plate 9 and holds it in position thereon. One-half of the wall 95 member 14 is cut away at the right of the flange 13 in order to allow the disk 7 to swing in and out between the flange 13 and the face plate 9.

To prevent the disk 7 from swinging too 100 far to the right a pin 12 is riveted to the disk. This pin projects into the curved guide slot 10 provided in the face plate 9 which limits its travel in either direction from the keyhole at a predetermined point. 105

As shown in Fig. 2, the screws 11 for fastening the face plate 9 to the door are so arranged that when the disks cover the key-

hole therein it also prevents access to these screws so that the face plate 9 itself cannot be tampered with.

I claim:

5 In a guard for a keyhole, the combination of a rod mounted to rotate parallel to the keyhole, a locking plate mounted on one end of the said rod, a guard disk mounted on the other end of said rod, said guard disk being adapted to be swung in front of one end of the keyhole on the swinging of said locking plate in front of the other end of the keyhole, said locking plate having an opening therein, a key adapted to pass
10 through the opening in said locking plate and into the keyhole to hold said locking
15

plate and said guard disk from swinging away from each end of the keyhole, a casing surrounding said guard disk, said casing having an opening in the front thereof and in line with the keyhole, a guide slot in said casing, a pin on said guard disk to engage said guide slot and stop said guard disk in a predetermined position when swinging away from the keyhole, said guard 20 and its casing being mounted on the outside 25 of the door.

In testimony whereof I affix my signature.

JOHN E. POWERS.
